(57) **CLAIM**

The ornamental design for a controller for medical apparatus, as shown and described.

DESCRIPTION

FIG. 1 is a front, right side and top perspective view of a controller for medical apparatus, showing our new design; FIG. 2 is an enlarged front elevational view thereof; FIG. 3 is an enlarged rear elevational view thereof; FIG. 4 is an enlarged top plan view thereof; FIG. 5 is an enlarged bottom plan view thereof; FIG. 6 is an enlarged right side elevational view thereof; FIG. 7 is an enlarged left side elevational view thereof; and, FIG. 8 is an enlarged fragmentary perspective view of the portion thereof surrounded by box 8 in FIG. 1, showing the power button part.

The broken lines immediately adjacent to the shaded areas and the claimed areas in the views represent the boundaries of the design while all other broken lines are included for the purpose of illustrating environmental structure and form no part of the claimed design. The stippling is used in the drawings to differentiate between the stippled and unstippled areas.
